COOKING STOVE.

No. 17,420.

Patented June 28, 1887.

UNITED STATES PATENT OFFICE.

WILLIAM J. DODD, OF LOUISVILLE, KENTUCKY, ASSIGNOR TO FISHER
BROTHERS & CO., OF SAME PLACE.

DESIGN FOR A COOKING-STOVE.

SPECIFICATION forming part of Design No. 17,420, dated June 28, 1887.

Application filed May 31, 1887. Serial No. 239,891. Term of patent 7 years.

To all whom it may concern:

Be it known that I, WILLIAM J. DODD, a citizen of the United States, residing at Louisville, Jefferson county, Kentucky, have invented and produced a new and original Design for Stoves, of which the following is a specification, reference being had to the accompanying photograph, forming part thereof, said photograph being a perspective view 10 of a stove embodying my design.

My new design is characterized by the doors A and B, ornamented by a groundwork of granular roughenings embellished by representations of chrysanthemum-vines; by the 15 skirtings B, ornamented by groundwork having granular roughenings embellished by representations of chrysanthemum-vines, and by legs C, which have their prominent faces embellished by representations of chrysanthemum-leaves.

I claim—

1. The design for a stove herein shown and described, the same consisting of doors ornamented by groundwork of granular roughenings embellished by representations of chrys- 25

anthemum-vines, and skirtings ornamented by a groundwork of granular roughenings embellished by representations of chrysanthemum-vines, by legs having their prominent faces embellished by representations of chrysanthemum-leaves, as shown. 30

2. The design for a stove herein shown and described, the same consisting of a door ornamented by a groundwork of granular roughenings embellished by representations of chrysanthemum-vines, as shown. 35

3. The design for a stove herein shown and described, the same consisting of a skirting ornamented by a groundwork of granular roughenings embellished by representations of chrysanthemum-vines, as shown. 40

4. The design for a stove herein shown and described, the same consisting of legs having their prominent faces embellished by representations of chrysanthemum-leaves, as shown. 45
